CONTROL SYSTEM UTILIZING SINGLE POINT IGNITION

Ernst Witzel, Milwaukee, Wis., assignor to Milwaukee Gas Specialty Company, Milwaukee, Wis., a corporation of Wisconsin

Application May 8, 1947, Serial No. 746,780

18 Claims. (Cl. 158—131)

1

This invention relates, in general, to ignition systems, and has particular relation to an improved single point ignition system for fuel burners.

While the particular embodiment of the invention which I shall describe hereinafter in connection with the drawings is a single point ignition system adapted for use with domestic gas ranges, it is to be understood that the invention is not limited to such use but may be employed for all similar purposes, for example, in connection with various commercial forms of apparatus having a baking oven burner, broiler oven burner, or other burner remotely located relative to the pilot burner.

In the usual domestic gas range, the pilot burner is in the form of a single constantly burning pilot located in juxtaposition to the top burners at the upper part of the range, and the baking oven, broiler, or like burners are located in the lower part of the range. Although the top burners are usually provided with a constantly burning pilot burner for lighting the same, at the present time a match is usually employed for lighting the baking oven, broiler or like burners.

The stooping and hazards of lighting an oven burner or the like with a match are well known in the art.

On the other hand, an all gas ignition system has advantages over electric systems, and it does not require an outside or external supply of electric power and will maintain supply of gas to pilots, whereas a failure of an outside or external source of electric power will interrupt the pilot operation. In general, electric power failure would automatically shut off the gas supply, i. e., make the functioning of a gas appliance dependent upon another utility.

My copending applications, Serial No. 738,412, filed March 31, 1947, and Serial No. 748,969, filed May 19, 1947 and now Patent No. 2,527,286, and the copending application of Russell Matthews, Serial No. 742,017, filed April 17, 1947, and now Patent No. 2,578,194, provide an improved system of flash tubes and intermediate pilot means for assuring ignition of a pilot in juxtaposition to the oven or like burner from a constantly burning top pilot; also improved single point ignition systems wherein means, shown in the form of thermally responsive means, is provided for extinguishing the intermediate pilot means and establishing a flow of fuel to the oven or like burner after a time delay following ignition of the burner pilot, and improved

2

thermoelectric control devices and other instrumentalities for accomplishing the new and advantageous results therein set forth.

In my copending application, Serial No. 5 744,905, filed April 30, 1947, the time delay is obtained by an orifice limiting the escape of the air compressed by the gas line pressure.

One of the main objects of the present invention is to provide a simple, improved and effective single point ignition system which will provide the advantageous results obtained with the systems disclosed and claimed in the above identified copending applications, and in which the time delay does not require thermally responsive means and is not dependent upon the gas pressure in the fuel supply line.

Another object of the invention is to provide a time delay which will prevent the flow of gas to the burner when after some operation the gas cock or other gas shut-off means is closed and immediately opened again.

Another object of the invention is to provide a single point ignition system of the class described in which the fuel supply for the one or more intermediate pilots is definitely shut off after a given time interval and independently of the valve controlling the supply of fuel to the main burner.

Another object of the invention is to provide 30 means wherein the time delay is set into operation manually by manipulation of the gas cock or other gas shut-off means.

Another object of the invention is to provide for a system of the class described, improved 35 shut-off and time delay means incorporated in a single device and a thermoelectric generator (such as a thermocouple or thermopile) operated device adapted to be separately installed.

Another object of the invention is to provide 40 a single point ignition system and instrumentalities therein, as will hereinafter appear, having various features of novelty and advantages, and which are particularly characterized by their simplicity in construction, their economy in manufacture and installation, and their effectiveness in use.

Further objects and advantages of the invention will appear from the following detailed description, taken in connection with the accompanying drawings which illustrate the manner of constructing and operating an illustrative embodiment of the invention.

In the drawings:

Figures 1 and 1A are parts of a diagrammatic view which, when placed with Figure 1A to the

right of Figure 1 and the line B—B of Figure 1A on the line A—A of Figure 1, form a complete diagrammatic view of one form of single point ignition system embodying the present invention; and

Figure 2 is a fragmentary sectional view through the shut-off and time delay device taken on the line 2—2 of Figure 1.

Referring now to the drawings, the burner 1 is the baking oven, broiler, or other remote burner. It is usually located in the lower part of the range or other appliance.

The pilot 2 is the constantly burning pilot. It may be, for example, the top pilot for the top burners of a gas range or other constantly burning pilot. The pilot 2 is usually located in the upper part of the appliance.

A fuel supply pipe 3 leads to the burner 1 for the delivery of gaseous or other fuel thereto, for example, through a mixing chamber 4 to which air is admitted through adjustable air inlets (not shown) as well understood in the art. The flow of gas through the pipe 3 is controlled by a shut-off and time delay device 5 and by a thermoelectric generator (such as a thermocouple or thermopile) operated device 6.

The oven or like burner 1 is provided with an oven or like pilot 7 for igniting it. A flash tube 8 opens at its upper end directly beneath the flame 9 of the constantly burning pilot 2. This tube extends vertically downwardly from the pilot 2, and opens at its lower end at 10 directly above the flame 11 of an intermediate pilot 12. The intermediate pilot 12 is spaced laterally from another intermediate pilot 13 in juxtaposition or igniting relation with respect to the oven pilot 7. The lower end of the tube 8 has a branch 14 extending laterally therefrom and opening at its outer end at 15 directly above the flame 16 of the intermediate pilot 13.

The shut-off and time delay device 5 comprises valve body parts 20, 21, 22, 23, and 24. The valve body part 20 has an inlet 26, and valve body part 21 has an outlet 27. Contiguous sections of the fuel supply pipe 3 are connected to the inlet 26 and outlet 27.

Gas shut-off means, shown in the form of a gas cock 28, has, for example, a tapered plug part rotatable in the wall of valve body part 20 adjacent to inlet 26. The shut-off means 28 has port means at 29 adapted by turning of the shut-off means to be placed in register with a passage 30 leading from inlet 26, and a passage 31 leading into a chamber 32. The shut-off means 28 is closed by turning it to position in which port means 29 is out of register with passages 30 and 31.

It is to be understood that any other desired type of gas shut-off means may be employed in lieu of the gas cock 28, for example a remotely controlled solenoid or motorized valve. In such case the valve may be of other than the tapered plug form selected for illustration, and the form of its cooperating seat may vary accordingly.

A port 33 is adapted to place chamber 32 in communication with a chamber 34 separated from chamber 35 by a diaphragm 36 clamped marginally between valve body parts 21 and 22. A valve seat surrounds the end of port 33 adjacent to chamber 32 for cooperation with a valve 37. Outlet 27 leads out from chamber 34. A passage 38 places chamber 32 in communication with chamber 35. A port 39 is adapted to place chamber 35 in communication with a chamber 40 separated from a chamber 41 by a diaphragm 42 clamped marginally between valve body parts 22

and 23. A valve seat surrounds the end of port 39 adjacent to chamber 40 for cooperation with a valve 43.

Valve or valve facing 43, which is preferably of yielding material and disc-like form, is fixedly secured to a valve stem 45 at the axis of the diaphragm 42, which is likewise secured at its axis to the stem 45 and valve 43. Valve stem 45 passes down through abutment discs or plates 46 at the axis of diaphragm 36. A coiled spring 47 is interposed between abutment disc 46 and valve body part 22 adjacent to port 39.

At its lower end the stem 45 has a rounded head 48 for cooperation with a cam 49 on the inner end of a stem 50 which extends inwardly from shut-off means 28. Valve 37 is carried by stem 45 near the lower end of the stem. A coiled spring 51, interposed between a flanged sleeve abutting cam 49 and valve body part 20, maintains the tapered plug part of gas shut-off means 18 seated in its bore in valve body part 20.

An outlet from chamber 40 is connected by a pipe or tube 55 with the intermediate pilots 12 and 13 for the purpose of supplying fuel thereto, as will presently appear. The constantly burning pilot 2 is supplied with fuel through a pipe or tube 56 connected at 57 with the fuel supply pipe 3 anterior of the shut-off and time delay device 5.

A perforated plate 58 and air filter 59 are clamped marginally between the outer end of valve body part 24 and a filter cover plate 60. A diaphragm 61, clamped marginally between valve body parts 23 and 24, separates chamber 62 from chamber 63. Chamber 62 opens outwardly through the perforations in plate 58 and through air filter 59 and a port 64 in filter cover plate 60 to atmosphere. A passage 65 leads from chamber 62 to a port 66 which is adapted to open into chamber 63, as will presently appear. A valve seat surrounds the end of port 66 adjacent to chamber 63 for cooperation with a valve 67 secured to diaphragm 61 at the axis thereof.

A passage 68 opens from chamber 41 into chamber 63. A passage 69 opens from chamber 62 to a tapered bore 70 near the outer end thereof. A passage 71 opens from the bore 70 near the inner end thereof into the chamber 41. The communication between chambers 62 and 41 through passages 69 and 71 and bore 70, and thereby the time delay, is adapted to be adjusted by screw 72 screwed into valve body part 23 and having a tapered pin cooperating with the tapered bore 70. The outer end of screw 72 has a kerf or other means for engagement, for example, by a screw driver or other suitable implement for adjusting the tapered pin to any desired position.

The device 6, which is operated by the thermoelectric generator, comprises a valve body part 75 having an inlet 76 and an outlet 77. Contiguous sections of the fuel supply pipe 3 are connected to inlet 76 and outlet 77, for example, by connecting the section of the pipe 3 leading from the outlet 27 of the shut-off and time delay device 5 to the inlet 76, and the section of the fuel supply pipe 3 leading to the main burner 1 to the outlet 77.

Internally, valve body part 75 has a generally L-shaped outlet chamber 78 having a longitudinally extending part in open communication with outlet 77 and a transversely extending portion defined by a cylindrical wall 79. An inlet chamber 80, in open communication with the inlet 76, terminates at its inner end in a generally annular chamber which embraces the wall 79.

The wall 79 terminates in an annular valve seat 81. An armature 82, of disc-like form, has a yielding or other suitable valve or valve facing 83 adapted to seat against the seat 81 to shut off the flow of gas from the inlet 76 to outlet 77 through chamber 78. A hood 84 is clamped to the valve body part 75 by a union nut 85, and preferably with a hood gasket therebetween.

In the illustrated embodiment of the invention, the means for operating the valve 83, and more particularly the means for opening this valve, is in the form of an electromagnet comprising a magnet frame or coil spool 86 and a coil 87. One side of the coil 87 is connected by a lead 88 to one of the thermocouple elements 89 of a thermocouple 90 or other suitable thermoelectric generator (such as a thermopile). The other element 91 of the thermocouple 90 is connected by a lead 92 to the other side of the coil 87.

The thermocouple 90 and lead connections therefor may be of the general character disclosed and claimed in Oscar J. Leins Patent No. 2,126,564, granted August 9, 1938, or it may be of any other suitable character, or in the form of a thermopile or other thermoelectric generator. The thermoelectric generator has one or more hot junctions, for example the hot junction 93, which is placed in position to be heated by the flames 94 and 94' of the intermediate pilot 13 and burner pilot 7.

In the illustrated embodiment of the invention, the electromagnet has a flux shell 95 and a spacer ring 96. The lower end of the coil spool 86 has an axial recess, and disposed in this recess and interposed between spool 86 and armature 82 is a coiled spring 97 which operates to move armature 82 to position to seat valve 83 on valve seat 81 when the electromagnet is deenergized. Energization of the electromagnet by heating of the hot junction of the thermocouple 90 is sufficient to lift valve 83 to open position against the action of spring 97. A hood spring 98, interposed between the top of the spool 86 and hood 84, seats the shell 95 in the valve body part at 100.

The operation of the system shown in the drawings is as follows:

When shut-off means 28 is turned to closed position, cam or actuator 49 lifts valve stem 45, thus closing valve 37 and opening valve 43, thereby opening the gas passage to intermediate pilots 12 and 13. No gas can flow to the intermediate pilots at this time however, since shut-off means 28 is closed.

Now, when gas cock or shut-off means 28 is turned to open position (see Figure 1), cam 49 releases valve stem 45 which may move into its lowest position (as viewed in Figure 1) after a given time interval. The time interval or time delay is accomplished as follows:

When valve stem 45 is raised, air in chamber 41 is displaced by way of passage 68, valve 67, passage 65, air filter 59 and port 64 to atmosphere. Valve 67 is lifted against the action of a spring 101 by means of excess pressure in chamber 41. Now, when gas cock or shut-off device 28 is moved to open position, valve stem 45 is allowed to drop or move back to its lowest position with the help of spring 47. This produces a suction in chamber 41, and valve 67 will close tightly so that air may enter chamber 41 only through passages 69 and 71 and bore 70. Bore 70 is controlled by tapered pin 72, and the amount of air permitted to enter can be adjusted accurately so that any desired definite time interval will elapse

before valve stem 45 is returned to its lowest position.

Upon opening valve 43, and as long as this valve and shut-off means 28 are open, gas is delivered from chamber 32 and through passage 38, chamber 35, port 39, chamber 40 and pipe or tube 55 to the intermediate pilots 12 and 13. The unburned gas from the intermediate pilots rises in the tube 8, which is relatively cool to permit this action. As it reaches the flame of constantly burning pilot 2, the gas is ignited and then recedes or flashes back to light the intermediate pilots 12 and 13.

During the time delay, thermocouple, thermopile or other thermoelectric generator 90 has been heated by intermediate pilot 13 to energize magnet coil 87 of valve 6 sufficiently to actuate the valve 83 to open position. Gas is now admitted to oven burner 1 and to burner pilot 7 which is ignited by intermediate pilot 13 and operates to ignite the oven burner. Burner pilot 7 now takes over the work of heating the thermoelectric generator 90.

Gas flow to oven burner 1 and burner pilot 7 is established when, with valve 83 open, the valve stem 45 returns to its lowest position thereby opening valve 37 and closing valve 43. The closing of valve 43 shuts off the supply of fuel to intermediate pilots 12 and 13, and, as a result, unnecessary or undesirable heating of the flash tube or other parts is avoided and economy is provided. The flash tube is always in a cool condition, and proper ignition is assured. In order to assure an early supply of gas to burner pilot 7 before intermediate pilots 12 and 13 are extinguished, the valves are arranged so that valve 37 will open before, and preferably a few seconds before, valve 43 is closed. This is due to the spacing of the valves 37 and 43 apart axially a greater distance than their cooperating valve seats, and to the fact that the valve 37 begins to open upon initial downward movement of the stem 45 as it is viewed in Figure 1; whereas at this time the valve 43 moves toward but has not reached full closed position.

The time delay prevents the flow of gas to the burner when after some operation the gas cock or other gas shut-off means is closed and immediately opened again. In such case the thermocouple or other thermoelectric generator would be still hot enough to hold the valve 6 open and supply the burner with gas which could not be ignited by pilots which have been extinguished by the closing of the gas cock. This gas would then escape unburned and constitute a hazard. However, the arrangement and time delay of the present invention provides:

1. That valve 37 is closed when the gas cock is opened, thus preventing supply of gas to the burner.

2. That a certain time is given the thermocouple or other thermoelectric generator to cool and deenergize and close valve 6 so that in case the flash tube system should fail to function, the valve 6 will be closed before valve 37 opens.

The sequence of operations shows that intermediate pilots 12 and 13 are definitely closed to gas supply after the time delay, no matter whether they have been ignited or not; thus no gas can escape in case of flash tube failure. The cam arrangement at 49 represents only one of many solutions within the scope of the present invention for lifting the valve stem 45 and operating the shut-off means 28 simultaneously.

Therefore the embodiment of the invention

shown in the drawings is for illustrative purposes only, and it is to be expressly understood that said drawings and the accompanying specification are not to be construed as a definition of the limits or scope of the invention, reference being had to the appended claims for that purpose.

I claim:

1. In apparatus of the class described, in combination, fuel supply means for supplying fuel to a main burner, to a constantly burning pilot burner and to intermediate pilot burner means, shut-off means in said fuel supply means and operable to establish and shut off the supply of fuel to the main burner and to said intermediate pilot burner means, an intermediate pilot burner valve for controlling fuel admission to the intermediate pilot burner means and operable to open position by actuation of said shut-off means to closed position, a main burner valve for controlling fuel admission to the main burner and operable to closed position by actuation of said shut-off means to closed position, means for actuating said intermediate pilot burner valve to closed position and said main burner valve to open position when said shut-off means is actuated to open position, and time-delay means coacting with said shut-off means whereby operation of said time delay means is initiated by operation of said shut-off means to open position, said time-delay means coacting with said intermediate pilot burner valve and with said main burner valve, whereby to produce a time delay after the opening of said shut-off means before opening of said main burner valve and closing of said intermediate pilot burner valve.

2. Apparatus according to claim 1 wherein the time delay means comprises a device having a chamber provided with means operated by said shut-off means for displacing the air from said chamber and wherein there is a restricted inlet to said chamber from atmosphere for delaying the establishment of fuel supply to the main burner and shut off of the fuel supply to the intermediate pilot burner means.

3. Apparatus according to claim 1 wherein the time delay means comprises a device having a chamber provided with means operated by said shut-off means for displacing the air from said chamber and wherein there is a restricted inlet to said chamber from atmosphere for delaying the establishment of fuel supply to the main burner and shut off of the fuel supply to the intermediate pilot burner means, and means for adjusting said restricted inlet.

4. Apparatus according to claim 1 wherein there is an igniting pilot burner in juxtaposition to said intermediate pilot burner means and said main burner, an electroresponsive valve in the fuel supply line for the main burner, and a thermoelectric generator subject to the heat of both said intermediate pilot burner means and said igniting pilot burner and connected in circuit with said electroresponsive valve for operation of said valve to open position by the heating of said thermoelectric generator.

5. In apparatus of the class described in combination, a device having a diaphragm with a fuel supply chamber on one side and an air chamber on its other side, said air chamber having an outlet opening from said chamber and a restricted inlet opening into said chamber from atmosphere, a valve for said outlet, a valve carried by said diaphragm, said valve having open position for entry of fuel into said fuel chamber and closed position shutting off the entry of fuel into

said fuel chamber, a fuel supply line, shut-off means in said fuel supply line, and means for opening said last valve by operation of said shut-off means to closed position, the restricted entry of air into said air chamber acting to maintain said valve open for an interval of time upon operation of said shut-off means to open position.

6. In apparatus of the class described, in combination, a device having a diaphragm with a fuel supply chamber on one side and an air chamber on its other side, said air chamber having an outlet opening from said chamber and a restricted inlet opening into said chamber from atmosphere, a valve for said outlet, a valve carried by said diaphragm, said valve having open position for entry of fuel into said fuel chamber and closed position shutting off the entry of fuel into said fuel chamber, a fuel supply line, shut-off means in said fuel supply line, means for opening said last valve by operation of said shut-off means to closed position, the restricted entry of air into said air chamber acting to maintain said valve open for an interval of time upon operation of said shut-off means to open position, and means for adjusting the restricted entry of air into said air chamber.

7. Apparatus according to claim 6 wherein the means for adjusting the restricted entry of air into said air chamber comprises a tapered duct and a cooperating adjustable tapered pin.

8. In apparatus of the class described, in combination, a valve body having a fuel inlet chamber and a first fuel outlet chamber, intermediate pilot burner means connected to receive fuel from said first fuel outlet chamber, a pair of intermediate fuel chambers one adapted for delivering fuel to said first fuel outlet chamber, a main burner connected to receive fuel from the other intermediate fuel chamber, passage means leading from said fuel inlet chamber to the intermediate chamber for delivering fuel to the intermediate chamber which delivers fuel to said first fuel outlet chamber, a first valve controlling communication between said fuel inlet chamber and the intermediate fuel chamber for connection with the main burner, a second and oppositely seating valve controlling communication between the other intermediate fuel chamber and said first fuel outlet chamber, a shut-off device, and means actuated by operation of said shut-off device for moving said first valve to closed position and said second valve to open position.

9. Apparatus according to claim 8 wherein there is a time delay device comprising a chamber provided with means for displacing air from said chamber and wherein there is a restricted inlet to said chamber from atmosphere for delaying closing of said second valve and opening of said first valve.

10. Apparatus according to claim 8 wherein there is pilot burner means, a fuel supply line, an electroresponsive valve in said fuel supply line, and a thermoelectric generator subject to the heat of said pilot burner means and connected in circuit with said electroresponsive valve for opening said valve by heating of said thermoelectric generator.

11. In apparatus of the class described, in combination, fuel supply means for supplying fuel to a main burner, to a constantly burning pilot burner and to intermediate pilot burner means, shut-off means in said fuel supply means operable to establish and shut-off the supply of fuel to the main burner and to said immediate pilot burner means, an intermediate pilot

burner valve for controlling fuel admission to the intermediate pilot burner means and operable to open position by actuation of said shut-off means to closed position, a main burner valve for controlling fuel admission to the main burner and operable to closed position by actuation of said shut-off means to closed position, means for actuating said intermediate pilot burner valve to closed position and said main burner valve to open position when said shut-off means is actuated to open position, time-delay means coacting with said shut-off means whereby operation of said time-delay means is initiated by operation of said shut-off means to open position, said time-delay means coacting with said intermediate pilot burner valve and said main burner valve whereby to produce a time delay after the opening of said shut-off means before opening of said main burner valve and closing of said intermediate pilot burner valve, and an electroresponsive valve in the fuel supply means for supplying fuel to the main burner, said electroresponsive valve being located on the posterior side of the main burner valve.

12. A safety shut-off device for a burner apparatus comprising, in combination, a valve body having a fuel inlet and a first fuel outlet for delivering fuel to both a main burner and an igniting pilot burner, said valve body having a second fuel outlet for delivering fuel to intermediate pilot burner means, a first valve operable to shut off flow of fuel through said first fuel outlet, a second valve connected for operation with said first valve and operable to shut off flow of fuel through said second fuel outlet, actuating means for actuating said valves together in one direction to close said first valve and open said second valve, said valves being operable in the opposite direction upon release of said actuating means to open said first valve and close said second valve, said first valve being arranged to open before said second valve closes, and time delay means for delaying closing of said second valve for a time interval after opening of said first valve.

13. A safety shut-off device according to claim 12 wherein the actuating means for actuating the valves in a direction to close the first valve and open the second valve comprises a shut-off valve positioned to control the delivery of fuel to the safety shut-off device through its inlet.

14. A safety shut-off device according to claim 12 wherein the actuating means for actuating the valves in a direction to close the first valve and open the second valve comprises a shut-off valve positioned to control the delivery of fuel to the safety shut-off device through its inlet, said shut-off valve operating to closed position when actuated to close the first valve and open the second valve.

15. A safety shut-off device according to claim 12 wherein the actuating means for actuating the valves in a direction to close the first valve and open the second valve comprises a shut-off valve positioned to control the delivery of fuel to the safety shut-off device through its inlet, said shut-off valve operating to closed position when actuated to close the first valve and open the second valve and, when operated to open position, releasing said first and second valves for opening of said first valve and closing of said second valve under control of the time delay means.

16. A safety shut-off device according to claim 12 wherein the time delay means comprises a device having a chamber provided with means for displacing air from said chamber by actuation of

the first valve to closed position and the second valve to open position, said device having a restricted inlet opening into said chamber.

17. A safety shut-off device according to claim 12 wherein the time delay means comprises a device having a chamber provided with a diaphragm connected for actuation with the first and second valves for displacing air from said chamber by actuation of the first valve to closed position and the second valve to open position, said device having a restricted inlet opening into said chamber.

18. A safety control device for burner apparatus of the class wherein there is a constantly burning pilot burner, a main burner remote from said constantly burning pilot burner, an igniting pilot burner in juxtaposition to the main burner for igniting the same, intermediate pilot burner means located between the constantly burning pilot burner and the igniting pilot burner for assuring ignition of the igniting pilot burner from the constantly burning pilot burner, a first fuel supply pipe for delivering fuel to both the main burner and the igniting pilot burner, a second fuel supply pipe for delivering fuel to the intermediate pilot burner means, a thermoelectric safety shut-off device positioned in the first fuel supply pipe and operable to shut off the fuel supply to the main burner and to the igniting pilot burner, a thermoelectric generator connected in circuit with the thermoelectric safety shut-off device and positioned to be heated both by the igniting pilot burner and the intermediate pilot burner means, said safety control device comprising a valve body having a fuel inlet, a first fuel outlet for

25 delivering fuel to said first fuel supply pipe and a second fuel outlet for delivering fuel to said second fuel supply pipe, a pair of connected valves one for shutting off the flow of fuel through said first fuel outlet and the other for shutting off the flow of fuel through said second fuel outlet, means for actuating said valves together in one direction to close the valve which shuts off flow of fuel through said first outlet and to open the valve which shuts off flow of fuel through said second outlet,

30 means for actuating said valves in the opposite direction upon release thereof to open the valve which shuts off flow of fuel through said first outlet and to close the valve which shuts off flow of fuel through said second outlet, the valve which shuts off flow of fuel through said first outlet being arranged to open before the other valve closes, and time delay means for delaying closing of the valve which shut off flow of fuel through said second outlet until the thermoelectric safety 35 40 45 50 55 60 65 70 75

shut-off device is operatively energized by the heat of the igniting pilot burner on the thermoelectric generator.
